UNITED STATES PATENT OFFICE

2,588,219

LATCH DAMPENING DEVICE

George B. Dorey, Westmount, Quebec, Canada,
assignor to Enterprise Railway Equipment
Company, Chicago, Ill., a corporation of Illinois

Application November 18, 1949, Serial No. 128,209

9 Claims. (Cl. 105—308)

1

This invention relates to a dampening device for a hopper door latch and is more particularly adapted for use with a latch bar pivotally mounted on a door for movement about its axis to engage with a shouldered keeper on the hopper.

An object of this invention is to dampen or cushion the releasing movement of a latch when violently displaced from its normal position such as occurs when such displacement is made by contact with a striker surface upon movement of a door to closing position. In the type of latch adapted to engage with a shouldered keeper having a beveled striker surface leading thereto and so arranged that the latch is displaced by riding on the keeper, it is desirable that the latch should be maintained in contact with the beveled surface throughout its movement and engage with the shoulder at the end of such movement. With the latch freely displaceable, there is a tendency for the latch bar to bounce away from the striker surface when the door is slammed to closed position. Should the impact of the latch on the keeper be in the form of a sudden action, such as occurs when the door is violently slammed or kicked to closed position, the latch bar is thrown away from the striker surface to the limits of its travel and, under certain circumstances, may again contact the striker to repeat the bouncing cycle before the door reaches closed position. It is therefore another object of this invention to control such movement and provide for delayed action in the releasing movement of the latch.

This invention is shown as applied to a hopper car of the type having a vertically swingable door pivotally mounted adjacent the upper margin of a discharge opening.

In the drawings:

Figure 1 is a view taken transversely of a portion of a hopper type car showing the center sill and side wall in section and a door for closing the discharge hopper opening in elevation, the door being shown in pendant open position;

Figure 2 is a detail sectional view taken generally along the line 2—2 of Figure 1 and showing the door in the closed and latched position; and

Figures 3 and 4 are views, at an enlarged scale, showing different operating positions of the latch mechanism and dampening means therefor which are constructed in accordance with this invention and embodied in the door and hopper construction shown in Figures 1 and 2.

A portion of a hopper type car is shown as including a center sill 9 and a car side wall 10 spaced outwardly therefrom. Interposed between

them is a hopper 11 having a discharge opening 12. The hopper 11 is defined in part by a floor 13 sloping downwardly towards the lower margin of the opening 12 and inner and outer side walls as indicated at 14 and 15 respectively. Sloping downwardly towards the upper margin of the opening 12 is a floor 16. Underlying the floor 16 and overlying the lower sloping floor 13 and side walls 14 and 15 there is a frame shown, generally, at 17 having hinge butts 18 along the upper part thereof. Pivotally mounted on the hinge butts 18 by hinge pins 19 is a door 20 which is adapted to be moved to an inclined closed position and be there retained by latching mechanism to be described.

The latching mechanism shown includes a latch bar 21 pivotally mounted at one end on a beam member 22 which is in turn securely mounted on the outer face of the door 20. Co-operating with the latch bar 21 at a location intermediate the ends thereof is a shouldered keeper or locking hook 23 which is secured to the hopper floor 13 and extended through an opening 24 formed in the door 20 and door beam member 22.

The keeper or hook 23 is provided with a shoulder 25 which engages with the latch bar 21 for retaining the door 20 in closed position and leading to this shoulder the keeper or hook 23 is provided with an inclined striker face 26 for engagement with the under side of the latch bar 21 and displacing the same upwardly as the door 20 is moved towards closed position. The outer end of the latch bar 21 is retained between the inner surfaces of extensions or arms 27 formed integrally with and extending upwardly from the beam member 22.

Pivotally mounted at 28 between the extensions or arms 27 there is a locking cam 29 which is adapted to engage in the usual manner for locking the latch bar 21 in closed position. The cam 29 in its released position is movable to an overbalanced position and it has been customary to limit the overbalancing movement a sufficient extent to maintain the cam 29 clear of the latch bar 21 so that it can move fully throughout its entire range of movement without interference therefrom.

The present invention contemplates broadly the provision of a weighted retarding element to act on the latch bar 21 as it approaches its final lifting stage. In carrying this out this element is embodied in the locking cam 29 in such a manner that the cam 29 in itself will perform the dual duty of locking the latch bar 21 and also act as

a damper therefor when the cam 29 is moved to an overbalanced released position. In practicing the invention the cam and dampening element 29 is formed with an arcuate surface 30 struck on an arc at a radius 31 extending from a center 31' spaced horizontally from the pivot axis 28 of the cam 29. A stop 32 is provided on the cam 29 to engage an edge 33 of the overlying extension or arm 27 to maintain the cam 29 in a definite position of release. The stop 32 holds the combination locking cam and dampening element 29 in a position where its center of gravity is located well to the right of the center 31' of the arcuate surface 30.

The cam 29, when in overbalanced released position as indicated in Figure 3, lies in the path of movement of the latch bar 21 and is positioned to contact the latter while it is still in contact with the upper portion of the striker surface 26 as indicated by the broken line showing of the latch bar 21. Continued movement of the latch bar 21 in an upward direction causes the arcuate surface 30 of the cam 29 to slide and roll along the upper surface 34 of the latch bar 21. This causes the cam 29 to turn on its pivotal axis and gradually moves the point of contact between the cam 29 and the latch bar 21 until the maximum displacement of the latch bar 21 is reached when, as shown in Figure 4, the line of contact between surface 34 of the latch bar 21 is at right angles to the radius 31 which now extends through the pivot axis 28 of the cam 29.

The necessity for overcoming the mechanical inertia of the cam and dampening element 29 and the rolling and sliding contact thus established between it and latch bar 21 has the effect of cushioning the upthrow of the latter and provide the equivalent of a delayed squeezing motion in contrast to a hammerlike blow.

Extending in opposite directions from the arcuate surface 30 and tangentially related thereto are flat surfaces indicated at 35 and 36 respectively. As shown in Figure 3 the flat surface 35 is preferably disposed to lie on a line contiguous to the upper surface 34 of the latch bar 21 as contact is established between the cam 29 and the latch bar 21 during the upward displacement of the latter. The other flat surface 36 comes into action only in the event that the upthrow of the latch bar 21 is of sufficient violence as to overbalance the cam 29. A tendency for the cam 29 to overbalance or turn too far in a counter clockwise direction is generally associated with a delayed return of the latch bar 21. The nose 37 at the extremity of the flat surface 36 then acts as a hammer to accelerate the downward movement of the latch bar 21 and assures its downward movement into latching engagement with the shoulder 25 on the keeper or hook 23 while the door closing movement is still in progress.

While I have shown my improvement as incorporated in the locking cam 29 it will be understood that the same is shown as a preferred embodiment making for a minimum number of parts and that the device may be incorporated in the form of one or more separate members.

Since certain changes can be made in the foregoing construction and different embodiments of the invention can be made without departing from the spirit and scope thereof, it is intended that all matter shown in the accompanying drawings and described hereinbefore shall be interpreted as illustrative and not in a limiting sense.

What is claimed as new is:

1. For combination with a hopper having a

discharge opening, a pivotally mounted door for closing said opening, and a latch bar pivotally mounted on said door to swing parallel thereto and biased to engage a shouldered keeper carried by said hopper, said keeper having an inclined striker surface to be engaged by said latch bar for displacing it upwardly when said door is swung to closed position and said latch bar is moved upwardly from a rest position to permit operative engagement between it and said keeper; a dampening element disposed in the path of upward movement of said latch bar and adapted to engage the same and retard such upward movement when it is moved a predetermined distance away from said rest position, and stop means for holding said dampening element in operative position with respect to said latch bar so that said dampening element can function as aforesaid.

2. The invention, as set forth in claim 1, wherein the dampening element is engaged by the latch bar intermediate its rest and latched positions and is adapted to move conjointly therewith.

3. The invention, as set forth in claim 1, wherein in the dampening element is pivotally mounted on the door to swing in the plane of the latch bar.

4. The invention, as set forth in claim 1, wherein in the dampening element is a cam pivotally mounted on the door and is adapted in one position to lock the latch bar in latched position and in another position to be engaged by said latch bar intermediate its rest and latched positions to perform its retarding function.

5. The invention, as set forth in claim 1, wherein the dampening element has an arcuate surface for engagement by the latch bar intermediate its rest and latched positions and is displaced upwardly therewith accompanied by sliding and rolling contact therebetween.

6. The invention, as set forth in claim 5, wherein in the dampening element has a nose portion constituting an extension from the arcuate surface generally parallel to the door and adapted to strike a downward blow on the latch bar at the upper limit of its travel.

7. The invention, as set forth in claim 5, wherein in a guiding wall for the latch bar is carried by the door and overlies the cam, and said cam has a stop comprising a part of the stop means for engaging an edge of said wall comprising another part of said stop means to hold said cam in position where its arcuate surface can be engaged by said latch bar.

8. For combination with a hopper having a discharge opening, a pivotally mounted door for closing said opening, and a latch bar pivotally mounted on said door to swing parallel thereto and biased to engage a shouldered keeper carried by said hopper, said keeper having an inclined striker surface to be engaged by said latch bar for displacing it upwardly when said door is swung to closed position and said latch bar is moved upwardly from a rest position to permit operative engagement between it and said keeper; a dampening element pivotally mounted on said door above said latch bar to swing in the plane thereof and having an arcuate surface whose center of curvature is spaced horizontally from the pivot axis of said dampening element when the same is to function as such and which surface is adapted to be engaged by said latch bar as it moves over said striker surface whereby said dampening element and latch bar move upwardly conjointly accompanied by

sliding and rolling contact therebetween and the

upward movement of the latter is correspondingly retarded.

9. For combination with a hopper having a discharge opening, a pivotally mounted door for closing said opening, and a latch bar pivotally mounted on said door to swing parallel thereto and biased to engage a shouldered keeper carried by said hopper, said keeper having an inclined striker surface to be engaged by said latch bar for displacing it upwardly when said door is swung to closed position and said latch bar is moved upwardly from a rest position to permit operative engagement between it and said keeper; a dampening element pivotally mounted on said door above said latch bar to swing in the plane thereof and having an arcuate surface whose center of curvature is spaced horizontally from the pivot axis of said dampening element when the same is to function as such and which surface is adapted to be engaged by

said latch bar as it moves over said striker surface whereby said dampening element and latch bar move upwardly conjointly accompanied by sliding and rolling contact therebetween and the upward movement of the latter is correspondingly retarded, and stop means on said door co-operating with said dampening element to position said arcuate surface in operative relation to said latch bar.
